UNITED STATES PATENT OFFICE

167,191

COMBINED BED HEADBOARD AND CHAIR UNIT

Carlo Bombara, Rosedale, N. Y.

Application May 14, 1952, Serial No. 19,720

Term of patent 7 years

(Cl. D5—4)

To all whom it may concern:

Be it known that I, Carlo Bombara, a citizen of the United States, residing in Rosedale, county of Queens, and State of New York, have invented a new, original, and ornamental Design for a Combined Bed Headboard and Chair Unit, of which the following is a specification, reference being had to the accompanying drawing, forming a part hereof.

Fig. 1 is a front elevation of a combined bed headboard and chair unit, showing my new design.

Fig. 2 is a plan view of the same.

Fig. 3 is an end elevation of the same.

I claim:

The ornamental design for a combined bed headboard and chair unit, as shown.

CARLO BOMBARA.
